ARBOR

Arthur Buescher, Detroit, Mich.

Application May 20, 1946, Serial No. 671,069
In Canada April 19, 1945

2 Claims. (Cl. 82—44)

1

This invention relates to arbors or mandrels, and has more especial reference to such devices which support tubular work and wherein it is desirable to expand the mandrel or arbor throughout an extended area or material length of the bore of the work in order to attain more or less even pressure throughout the bore, thus enabling such pressure to be relatively light and of a nature not to mar, distort, or disfigure the work.

Generally, the expanding arbors or mandrels as heretofore constructed, a pull-in tapered expander has been utilized which exerted most of its expanding effect on the outer end portion of the arbor or mandrel and frequently called for a degree of pressure which resulted in the formation of undesirable pressure marks on the bore of the work, and which in some cases were inadmissible so that the uses of such expanding arbors or mandrels have been limited.

This application is a continuation-in-part of my abandoned application, Serial No. 541,245, filed June 20, 1944, for Arbors.

The present invention so disposes an expander element within the arbor or mandrel that expanding pressure may be exerted remote from the end thereof and preferably at spaced intervals along the length thereof; and more particularly provides an expander having tapered steps in its length coaxing against tapered seats within the arbor or mandrel to provide spaced points or zones of expanding pressure along the length of the device.

A prime object is to provide an arbor or mandrel of the present character which has a pilot portion to facilitate rapid and accurate positioning of the work thereon, aided by a normally contracted tapered portion extending from said pilot portion to the outer free end of the arbor, and in combination with an expander for the latter.

Further, the said invention provides adjustable means limiting longitudinal arbor-expanding movement of the expander to prevent undue and inadvertent expansion of the device beyond a predetermined limit.

Still further, the said invention affords a seat in the outer end of the arbor or mandrel to cooperate with a supporting center in providing for expansion of that end of the said arbor or mandrel in combination with provision for expansion of the mandrel at a point or points remote from that end.

Additional or subsidiary objects and advantages resulting from the construction or operation of the invention as it may be carried into effect will become apparent as the said invention is hereinafter further disclosed and it will be noted that the invention is particularly, but not necessarily solely, intended for use on hydraulically operated machines.

In carrying the said invention into effect, I may provide an arbor or mandrel, having a work-receiving portion divided radially throughout a major part of its length from one end for expansion

2

within tubular work, which portion is contractile to a taper smaller at its outer or free end, and which portion extends from a work-positioning non-contractile pilot portion, with an expander in the form of a rod having conical steps thereon within the arbor or mandrel, the said conical steps being opposed by corresponding conical seats on and within the arbor, said rod being threaded into the inner end of the device so that said rod may be screwed into arbor-expanding impingement with the aforesaid conical seats to an extent limited by adjustable stop means, and a conical seat on the outer slotted end of the arbor to receive the conical end of a center. All of which is more particularly described and ascertained hereinafter, by way of example, having reference to the accompanying drawing, wherein:

Figure 1 is a longitudinal sectional elevation of an arbor or mandrel embodying the said invention (the spring jaws being contracted) together with the operating means;

Figure 2 is a longitudinal section of the principal parts of Figure 1, the spring jaws being engaged with a center and expanded to work-engaging position;

Figure 3 is a side elevation of the arbor with its jaws contracted;

Figure 4 is an end elevation of the arbor with its jaws contracted; and

Figures 5 and 6, respectively, are cross sections taken on the planes of line 5—5 and 6—6 of Figure 2.

Similar characters of reference indicate similar parts in the several figures of the drawing.

The numeral 5 indicates in general an arbor or mandrel, which in this case is provided with a driving portion 6 unitary with a driver head 7 and which may optionally be separate from or integral with the arbor 5. Said head 7 is attached, for example, to a driver 8 by means of screws 9 passing through enlarged openings 10 in the head 7 and permitting concentric or eccentric adjustment of said head through actuation of any desired number of screws 11 carried by the driver. Said driver 8 is mounted in any suitable manner so as to rotate the arbor or mandrel.

A work-receiving portion 14 of the arbor or mandrel is shown as being radially slotted throughout the major part of its length from the front or distal end, as indicated by reference characters 15, 16, and 17, thereby forming any suitable number of radially expansible fingers 18, 19, and 20. Reference character 21 indicates conventional work of a tubular character mounted on the said arbor or mandrel. Said fingers 16, 15, and 17 are inherently resilient so as to be biased to contract, even to the point of mutually contacting at the said front or distal end of portion 14, and the latter portion is thus tapered with its distal end smaller than the proximal or pilot end.

It is especially to be noted that said portion 14

is not slotted throughout and hence a truly cylindrical pilot portion 12 is provided. This portion 12 is important because after the work is applied over the tapered portion of the mandrel, it is snugly engaged by the pilot portion and accurately held while said portion 14 is expanded to grip and hold it.

Extending into the said mandrel from the rear end thereof is an expander in the form of a rod 22 provided at the forward end with an extension 23 of smaller diameter, the step between the parts of larger and smaller diameter 22 and 23 being coned or tapered, as at 24, and the distal end of the extension 25 being also coned or tapered as at 25. The rod 22 is slideable in the arbor and is operated manually or by power, for example, by means of screw threads 26 being attached to a plunger 13 of a conventional hydraulic cylinder D. Engaged with said threads 26 are adjustable locknuts 27 and 28 to act as stops to limit the extent or insertion of the expander rod into the arbor or drill.

Said arbor or mandrel and its resilient fingers are bored in counterpart of the expander rod 22 and its extension in such manner that conical or tapered seats 29 and 30 are provided to receive the conical or tapered steps 24 and 25 of the expander rod whereby, upon the said rod being moved into the arbor or mandrel to the required extent, the same expands the resilient fingers 18, 19, and 20 of the said arbor or mandrel at the seats 29 and 30, as will be readily understood.

The outer end of the resilient fingers of the arbor or mandrel is also provided with a conical seat 31 to receive the conical point of a center 32 which may also act as an expanding agent for the outer end of the said fingers when the outer end of the arbor or mandrel is pressed into supported engagement with the center in the usual manner.

It will be easily seen that the construction described provides for radial expansion of the fingers by internal pressure at a plurality of points or zones in their length insuring more even distribution of pressure throughout an extended area along the bore of the work in contrast to such expansion usually at a single point, and especially merely at or about the end portions of the arbor or mandrel as has heretofore been the general practice. As a result, in the present arrangement, the concentration of pressure at any point on the work may be lighter with equal holding effect, the slotting of the fingers may be quite fine or narrow and the tendency to produce pressure marks in the bore of the work greatly minimized.

Further, the provision of stops limiting the rectilinear expanding movement of the expander rod prevents undue pressure being applied to the work or breakage or distortion of the arbor or mandrel being brought about by careless application of expanding pressure to the fingers thereof in the absence of work supported thereon. Such spoilage of arbors or mandrels has heretofore been very high and costly.

It may be pointed out that this device is well adaptable to the particular job so that the utmost in accuracy may be attained and scoring, pressure marks, and so forth, such as have resulted from the use of the prior art devices may be avoided.

In so machining or fitting the device to the work, the bore of which has been determined, the arbor is expanded by means of the rod 22 in a grinding machine and is then ground while

so expanded accurately to an O. D. which constitutes a light but effective driving fit for the work. Thus, when the said rod 22 is partially withdrawn thereafter, the arbor will contract to tapered form, except for the pilot or butt portion 12, so that in use a succession of identical pieces of work may be quickly positioned onto the pilot or butt portion of the arbor, the rod 22 moved hydraulically into its arbor expanding position to the extent determined by the stop means 21, and the O. D. of the work thereafter ground accurately in relation to the bore with a minimum of manipulation and adjustment.

While not necessarily so limited in scope, the device is particularly suitable for the grinding of soft metal tubular sleeves such as valve guides wherein it is important that the previously ground bore should be in no way damaged or distorted, thus avoiding the exceedingly high spoilage on these parts unavoidable with the prior art.

This invention may be developed within the scope of the following claims, without departing from the essential features of the said invention, and it is desired that the specification and drawing be read as being merely illustrative of a practical embodiment of the said invention and not in a strictly limiting sense.

What I claim is:

1. In an arbor for internally supporting tubular work, a cylindrical work-holding body radially slotted from one end only to provide a plurality of expansion fingers all mutually connected at the other end of said body to form an expanding and non-expanding work-receiving arbor proportioned to fit within one end of the bore of the work, driving means connected to the non-expanding end portion of said body, and a finger-expanding rod longitudinally adjustable within said body, said rod having a plurality of tapered successively enlarged steps disposed axially thereon and said fingers having correspondingly positioned tapered and successively enlarged internal seats thereon for expanding engagement by said steps.

2. In an arbor for internally supporting tubular work, a cylindrical work-holding hollow body longitudinally slotted inwardly from one end and short of the other end of the work-holding portion of said body, said body between the slots and second-mentioned end having a work-engaging non-expandable pilot portion of approximately cylindrical form proportioned to fit within one end of the bore of the work, said body being inherently resilient to contract at the first-mentioned end to a normally tapered form, an expander rod operable in the hollow of said body having a plurality of spaced steps thereon, and said body having seats engageable by said steps in expanding said body, whereby said body may be expanded from its normally tapered form to a substantially non-tapered cylindrical form.

ARTHUR. BUESCHER.
